UNITED STATES PATENT OFFICE.

FRANK CARSON, OF CARO, MICHIGAN.

SORTING DEVICE.

1,245,086.

Specification of Letters Patent. Patented Oct. 30, 1917.

Application filed March 17, 1916. Serial No. 84,888.

To all whom it may concern:

Be it known that I, FRANK CARSON, a citizen of the United States, residing at Caro, in the county of Tuscola and State 5 of Michigan, have invented new and useful Improvements in Sorting Devices, of which the following is a specification.

This invention relates to sorting devices which are utilized to separate defective 10 beans and other objects from perfect ones of their kind, the invention having special reference to that class of devices in which the objects to be separated are carried by a conveyer in full view of the operator or attendant, said conveyer having pockets or 15 cells with yielding bottom members through which the defective objects may be pushed by the fingers of the operator, leaving the perfect objects to be discharged over the 20 conveyer.

One object of the invention is to simplify and improve the construction of the endless conveyer which constitutes an important part of the device.

Another object of the invention is to produce simple and improved means for conveying the objects from a source of supply 25 and depositing the same in the cells or pockets of the conveyer.

A further object of the invention is to produce a cylindrical distributing member, operated in conjunction with the endless conveyer and adapted to distribute the objects to be separated in the pockets of the 30 conveyer, one object in each pocket.

With these and other ends in view which will readily appear as the nature of the invention is better understood, the same consists in the improved construction and novel 35 arrangement and combination of parts which will be hereinafter fully described and particularly pointed out in the claims.

In the accompanying drawings has been 40 illustrated a simple and preferred form of the invention, it being, however, understood that no limitation is necessarily made to the precise structural details therein exhibited, but that changes, alterations and modifications within the scope of the claims may be 45 resorted to when desired.

In the drawings,—

Figure 1 is a top plan view of a machine constructed in accordance with the invention.

Fig. 2 is a side elevation.

55

Fig. 3 is a longitudinal vertical sectional view taken on the line 3—3 in Fig. 1.

Fig. 4 is a transverse sectional view taken on the line 4—4 in Fig. 1.

Fig. 5 is a perspective detail view of the 60 distributing cylinder.

Fig. 6 is a sectional detail view, enlarged, of a portion of the endless conveyer taken on the line 6—6 in Fig. 1.

Fig. 7 is a bottom plan view, showing a 65 small portion of the top lead of the endless conveyer.

Fig. 8 is a top plan view of the same.

Fig. 9 is a sectional detail view taken on the line 9—9 in Fig. 2.

70

Fig. 10 is a sectional detail view taken on the line 10—10 in Fig. 2.

Corresponding parts in the several figures are denoted by like characters of reference.

The main frame 15 of the machine is provided with bearings for shafts 16, 17 and 18 over which an endless conveyer C is trained, said shafts being provided with sprocket wheels 19 engaging the links of the conveyer. The boxes or bearings of at least one of the 75 shafts are adjustably connected with the frame by means of set screws 20, this construction being shown applied to the shaft in Fig. 2 where one of the bearings is indicated by 21, and the set screws 20 are shown 80 extending through a slot 22 in the frame. This construction enables the conveyer C to be properly tensioned so that the top lead of said conveyer will be maintained in a 85 level condition, the supporting shafts 16 and 17 being arranged substantially in a horizontal plane, and the sprocket wheels 19 being of equal size.

The conveyer C in its preferred construction comprises chains 23, one at each side, 90 said chains being trained over the sprocket wheels 19, and said chains being connected together by cross bars 24, 25 supporting the links 26 which are suitably spaced apart to produce cells or pockets D of suitable 100 dimensions. Some of the links are provided with downwardly extending offsets 27, clearly seen in Fig. 6, said offsets serving to support additional cross bars 28 which are disposed intermediate the cross bars 24, 25, 105 relatively near the cross bars 25 which are at the front with respect to the upper lead when the conveyer is moving in a direction

indicated by the arrow in Fig. 6. The several pockets are provided with leaves or bottom members 29, the same being hingedly connected with the cross bars 25 and positioned with their free ends beneath and abutting on the cross bars 24, each bottom member being pressed by the arm 30 of a spring, a portion of which is coiled about one of the cross bars 25, as seen at 31, said 10 spring having another arm 32 that engages the cross bar 28. It will be seen that by this simple construction, the endless conveyer is made to comprise a large number of pockets, each of which has a yieldably supported leaf or bottom member which may be readily depressed against the tension of its actuating spring to enable an object supported thereon to be pushed through the top leaf of the conveyer. It will also be seen 15 that by properly spacing the cross bars 28 from the cross bars 25, the said cross bars 28 will not lie in the path of an object that is being pushed over the supporting leaf or bottom member which is directly in the 20 front thereof, as seen in Figs. 6 and 7. The entire conveyer being constructed of metal will be rigid, and will not be liable to sag when in operation, especially when properly tensioned by previous adjustment of the 25 tensioning shaft 18.

The frame of the machine supports at one end thereof the receptacle 33 in which operates a feeder F which consists of an endless conveyer composed of slats 34 which 30 are flexibly connected together by means of link belts 35 trained over sprockets 36, 37, and 38 on shafts 39, 40 and 41, said shafts being supported for rotation in boxes or bearings carried by the frame structure. 35 The shafts 39, 40 and 41 are arranged at the corners of a triangle, the apex of which dips into the receptacle 33. The boxes in which the shafts 39, 40 are supported for rotation are vertically adjustable in guides 42 by 40 means including screw threaded rods 43 and wing nuts 44, thereby enabling the conveyer chains 35 to be tensioned or tightened, as may be required. The boxes supporting the shaft 41 are longitudinally adjustable 45 with respect to the longitudinal frame bars 46, on which they are mounted, by means of set screws 47 engaging the boxes 48 through slots 49 in the frame bars 46, thereby enabling the lowermost portion of the conveyer or feeder F to be adjusted longitudinally to the most advantageous position. The slats 34 of the feeder F are provided 50 with cups 50, each of said cups being of a proper size and shape to contain a single bean, pea or other object of the kind for the separation of which the machine is provided.

The superstructure of the frame which supports the feeder F also supports a shield 55 51 which is disposed adjacent to the rear-

ward lead of the feeder, said shield being equipped with a plurality of chutes 52 formed by partitions 53 and rear wall portions 54, the latter being provided at their upper ends with rearwardly extending 70 tongues 55 pointing in the direction of the forward lead of the feeder. The chutes 52 are arranged in registry with the cups 50 on the feeder slats so that the contents of the separate cups will be dumped or discharged into separate chutes. The shield 51 and the wall member 54 which constitute, respectively, the front and rear walls of the chutes are provided at their lower ends with swelled portions 56, 57 constituting the walls 80 of an approximately cylindrical housing, said swelled portions being, however, spaced apart so as to form a slot 58 in the lower portion of said housing. Supported for rotation in the said housing is the distributing cylinder G, the same consisting of a shaft 59 having radial longitudinal wings 60 and transverse partitions 61 coöperating to form cells 62, the area of the outermost 85 portions of which correspond with the area 90 of the pockets D of the endless link belt constituting the conveyer C. The shaft 59 is provided with sprocket wheels 63 engaging the conveyer chains 23, so that the distributing cylinder will be operated by and 95 concurrently with the conveyer C in such a fashion that the contents of each of the cells 62 of the distributing cylinder will be discharged into one of the pockets D of the conveyer.

The shaft 39 of the feeder F may be driven by a motion transmitted thereto by means of a chain 64 from the shaft 16. The machine is preferably driven by power applied to the shaft 17 at the discharge end of the 100 conveyer C, said shaft 17 having been shown as provided with a band wheel 65, although it is to be understood that the machine may be driven by hand, or by power applied in whichever manner and at whichever 105 point shall be regarded as most convenient.

In the operation of this device, the beans or other objects that are to be separated are placed in the receptacle 33. The feeder F having the cups 50 will lift the beans from 110 the receptacle and carry them to the chute 52, whereby they are conveyed to the cells of the distributing cylinder, which latter, being operated conjointly with the conveyer C, will serve to distribute the beans singly in the pockets D, the arrangement being such that a bean will be placed in each one of the pockets. The beans will thus be spread out evenly before the gaze of the operator who by pressing or pushing the defective beans will force the same through the top lead of the conveyer and into the pan or receptacle 66 placed underneath. The good beans will be discharged over the 125 tail end of the conveyer C to a suitable re- 130

ceptacle provided for the purpose but not shown. It is obvious that the machine may be speeded to suit the skill and convenience of the operator.

5 Having thus described the invention, what is claimed as new is:—

1. In a machine of the class described an endless conveyer having a substantially horizontal top lead, said conveyer being provided with pockets arranged in transverse and also in longitudinal alinement, in combination with a distributing cylinder supported for rotation adjacent to the top lead of the conveyer, said cylinder having rows of cells each corresponding with a transverse row of pockets in the conveyer, means for feeding material to the distributing cylinder, and means for rotating the cylinder concurrently with the operation of the conveyer to space 10 the rows of cells in the distributing cylinder successively in discharging relation with respect to the rows of pockets in the conveyer.

2. In a machine of the class described an endless conveyer having a substantially horizontal top lead, said conveyer being provided with pockets arranged in transverse and also in longitudinal alinement, in combination with a distributing cylinder supported for rotation adjacent to the top lead of the conveyer, said cylinder having rows of cells each corresponding with a transverse row of pockets in the conveyer, means for feeding material to the distributing cylinder, and means for rotating the cylinder concurrently with the operation of the conveyer to space 25 the rows of cells in the distributing cylinder successively in discharging relation with respect to the rows of pockets in the conveyer; in combination with a housing for the distributing cylinder having a longitudinal slot in the bottom portion thereof to permit communication between a row of cells of the cylinder and a row of pockets in the conveyer.

3. In a machine of the class described, an endless conveyer having a substantially horizontal top lead, said conveyer being provided with pockets arranged in transverse and also in longitudinal alinement, in combination with a distributing cylinder supported for rotation adjacent to the top lead of the conveyer, said cylinder having rows of cells each corresponding with a transverse row of pockets in the conveyer, means for feeding 30

material to the distributing cylinder, and means for rotating the cylinder concurrently 55 with the operation of the conveyer to space the rows of cells in the distributing cylinder successively in discharging relation with respect to the rows of pockets in the conveyer; in combination with a housing for the distributing cylinder having a longitudinal slot 60 in the bottom portion thereof to permit communication between a row of cells of the cylinder and a row of pockets in the conveyer, and a plurality of feed chutes communicating 65 with a row of cells in the distributing cylinder through the top portion of the housing.

4. In a sorting machine, a sorting belt 70 consisting of a pair of chains, sprocket carrying shafts over which said chains are guided, transverse rods connecting said chains, links carried by the transverse rods and coöperating therewith to constitute pockets, some of said links having offset portions, auxiliary transverse rods carried by said offset portions, bottom members pivoted on the alternately disposed transverse rods and having free ends adjacent to the intermediate transverse rods, and springs coiled 80 on the rods on which the bottom members are pivoted and having arms engaging, respectively, the pivoted bottom members and the auxiliary transverse rods supported by the offset portions of the links. 85

5. In a machine of the class described, a sorting belt having pockets each including portions of two transverse parallel rods and links connecting the same, a third transverse rod supported intermediate and offset from 90 the first mentioned rods, a bottom member pivoted on one of the first mentioned rods and having a free end portion extending adjacent to the other of said first mentioned rods, and a spring coiled on the rod on which 95 the bottom member is pivoted, said spring having arms one of which engages the pivoted bottom member, the other arm engaging the transverse rod offset from the first mentioned rods. 100

In testimony whereof I affix my signature in presence of two witnesses.
